UNITED STATES PATENT OFFICE.

PHELOGAN BUTAUD, OF WEST COLUMBIA, TEXAS.

PREHEATER.

Application filed March 6, 1922. Serial No. 541,459.

To all whom it may concern:

Be it known that I, PHELOGAN BUTAUD, citizen of the United States, residing at West Columbia, in the county of Brazoria and State of Texas, have invented certain new and useful Improvements in a Pre-Heater, of which the following is a specification.

This invention relates to new and useful improvements in a pre-heater.

One object of the invention is to provide a device of the character described, specially designed for use in connection with a boiler for heating the water before it enters the boiler.

Another object of the invention is to provide a pre-heater so constructed that the exhaust from the engine may be utilized for heating said water before it enters the boiler.

With the above and other objects in view the invention has particular relation to certain novel features of construction, operation and arrangement of parts, an example of which is given in this specification and illustrated in the accompanying drawings, wherein:—

Figure 1 is an end view of the pre-heater.

Figure 2 is a side view.

Figure 3 is a vertical sectional view taken on the line 3—3 of Figure 2, and

Figure 4 is a vertical sectional view taken on the line 4—4 of Figure 1.

Referring now more particularly to the drawings, the numeral 1 designates the outer shell, or casing which may be of any desired contour and which is preferably constructed of sheet metal. To one side of this casing there is secured a vertical float chamber 2. The numeral 3 designates an inlet water pipe through which water is admitted, and this pipe separates into the branch pipe 4, 4, which enters through the top of the casing. Underneath the discharge

ends of these branch pipes there is located a series of pans 5, 5, 6, 6, 7, 7. These pans are supported on suitable cross rods 8, whose ends are supported on the cleats 9, which are fastened on the inside of the side walls of the casing. The pans of each series are enlarged downwardly, that is each pan is somewhat larger than the one immediately above it, so that the overflow of water from any pan will be caught by the one beneath it. These pans stand full of water and the overflow from them keep the casing

filled with water up to the level of the overflow pipe 10.

At one end of the casing there is an enclosed steam chamber 11 into which the exhaust gases or steam enters through the pipe 12. At the opposite end of the casing there is a transverse partition plate 13 extending from side to side of the casing and extending from the bottom thereof up slightly above the overflow pipe 10, thus forming a chamber 14 which is open at the top and from the bottom of which there leads a drain pipe 15 through which condensed water may be drained from said last mentioned chamber. The chambers 11 and 14 are connected by tubes 16. The steam or exhaust gases entering the chamber 11 pass through said tubes into the chamber 14 and pass thence up around the pans and out through the discharge pipe 17. It is to be noted that the tubes 16 are submerged in water and heat the same, and the pans 5, 6, and 7 are also filled with water, which is heated by the hot steam, or hot gases, by which they are enveloped. A glass gage 18 is connected into the casing above and below the tubes 16. This is provided for the purpose of ascertaining the amount of water in the casing. Leading from the bottom of the casing there is an outlet line 19 which leads to the pump by which the heated water is pumped into the boiler. Water is admitted into the float chamber 2 through the opening 20, and in this chamber there is a float 21 having the stem 22 which is connected to a suitable shut off valve 23, of conventional form, which controls the line 3. When the water rises in said chamber it will lift the float and close said valve to shut off the inflow of water and as the water falls in said chamber the float will fall and open said valve to permit the inlet of water.

Hot water is thus provided for the boiler by utilizing the heat from the exhaust which would otherwise be wasted and a great saving of fuel is thus effected.

What I claim is:—

1. A pre-heater, including a casing, a water pipe entering the top of the casing, means for controlling the inflow of water, a pan in the upper part of the casing aligned underneath the discharge end of said water pipe, an outlet pipe leading from said casing, chambers on opposite sides of the casing, one of which is open on one side,

an inlet entering the other chamber, a conduit connecting said chambers providing for the passage of a heating medium therethrough.

2. A pre-heater, including a casing, a plurality of pans arranged one above the other in the upper part thereof, an inlet water pipe entering the casing, whose discharge end is aligned above said pans, a discharge pipe leading from the casing, an enclosed chamber arranged within the casing at one side, a heating medium inlet entering said chamber, a chamber, open above, arranged within the casing opposite the first mentioned chamber, tubes connecting said chambers providing for the passage of a heating medium from the first mentioned chamber to the other chamber, and an exhaust pipe for said heating medium leading from the casing.
3. A pre-heater, including a casing, a series of pans arranged one above the other in the upper part of the casing, an inlet water pipe, whose discharge end is aligned above said pans, an outlet water pipe leading from said casing, chambers formed within the casing beneath said pans, said chambers being at opposite sides of the casing and one of them being open above an inlet for a heating medium entering the other chamber, tubes connecting said chambers, providing for the passage of a heating medium from the closed chamber to the open chamber, an exhaust outlet for said heating medium, and means for automatically controlling the passage of water through said inlet water pipe.

ing medium entering the other chamber, tubes connecting said chambers, providing for the passage of a heating medium from the closed chamber to the open chamber, an exhaust outlet for said heating medium.

4. A pre-heater, including a casing, a series of pans arranged one above the other in the upper part of the casing, an inlet water pipe, whose discharge end is aligned above said pans, an outlet water pipe leading from said casing, chambers formed within the casing beneath said pans, said chambers being at opposite sides of the casing and one of them being open above an inlet for a heating medium entering the other chamber, tubes connecting said chambers, providing for the passage of a heating medium from the closed chamber to the open chamber, an exhaust outlet for said heating medium, and means for automatically controlling the passage of water through said inlet water pipe.

In testimony whereof I have signed my name to this specification in the presence of two subscribing witnesses.

PHELOGAN BUTAUD.
